CLAIM

The ornamental design for a vacuum lunch box, as shown and described.

DESCRIPTION

FIG. 1 is a top perspective view of a vacuum lunch box showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof;

FIG. 7 is a rear elevation view thereof;

FIG. 8 is a bottom plan view of the lid portion, shown separately to show aspects of the design that are not visible when combined;

FIG. 9 is an exploded top perspective view thereof; and, FIG. 10 is an exploded bottom perspective view thereof.

The broken lines shown in the figures depict portions of the vacuum lunch box that form no part of the claimed design.

1 Claim, 5 Drawing Sheets
